(57) CLAIM

The ornamental design for an hour glass cup, as shown and described.

DESCRIPTION

FIG. 1 is a perspective view showing my new design for an hour glass cup in a fully closed position,

FIG. 2 is a side elevational view thereof,

FIG. 3 is a top plan view thereof,

FIG. 4 is a perspective view thereof with the lid removed for ease of illustration;

FIG. 5 is a side elevational view thereof; and,

FIG. 6 is a top plan view thereof.

The bottom view is plain and unornamental.
